UNITED STATES PATENT OFFICE.

HOBART B. IVES, OF NEW HAVEN, CONNECTICUT.

DESIGN FOR A BEAD-ENGAGING THIMBLE.

SPECIFICATION forming part of Design No. 28,860, dated June 14, 1898.

Application filed December 31, 1897. Serial No. 665,242. Term of patent 14 years.

To all whom it may concern:

Be it known that I, HOBART B. IVES, of New Haven, in the county of New Haven, and in the State of Connecticut, have invented a certain new and original Design for a Bead-Engaging Thimble for Adjustable Window-Bead Fasteners; and I do hereby declare that the following is a full, clear, and exact description thereof, reference being had to the accompanying drawings, in which—

Figure 1 shows, in plan view and on an enlarged scale, a sash-bead-engaging thimble formed in accordance with my improved design; Fig. 2, a side view of the same; Fig. 3, a view of a section on line $x-x$ of Fig. 1, and Fig. 4 a view of a section on line $y-y$ of Fig. 2.

Letters of like name and kind refer to like parts in each of the figures.

The essential feature consists of the unitary design as made the subject of description and illustration.

As shown in the drawings, the thimble formed in accordance with my design has a cup-shaped body A, made tapering from its outer to its inner end, with a bottom B in the form of a flat table, made thicker than the

sides of the body and provided with a slot b, extending nearly from one side to the other of such bottom.

On the outside of the side walls of the body A are the two longitudinal ribs a a, situated at points diametrically opposite each other at the ends of a line extending across the body A at right angles to the slot b.

Around the upper or outer edge of the body A and extending out over the upper or outer ends of the ribs a a is a lip or flange a', whose inner edge or periphery is continuous or unbroken.

Having thus described my invention, what I claim, and desire to secure by Letters Patent, is—

The design for a bead-engaging thimble for adjustable window-bead fasteners, as herein shown and described.

In testimony that I claim the foregoing I have hereunto set my hand this 29th day of December, A. D. 1897.

HOBART B. IVES.
